UNITED STATES PATENT OFFICE.

CHARLES A. WARDEN, OF HUNTINGTON, WEST VIRGINIA.

COAL-MINING MACHINE.

Application filed May 21, 1924. Serial No. 714,822.

This invention relates to improvements in coal mining machines of the class adapted for loading loose coal from the floor of rooms or entries into cars by means of which it may be transported to tipplers.

An important object of the invention is to provide a loader which is capable of being dumped under a loose pile of coal and may then be moved laterally, under the pile of coal, for causing the latter to be automatically placed upon the loader in a position to be conveyed to a mine car.

A further object of the invention is to provide means for combining or uniting standard forms of shortwall mining machines with standard forms of simple conveyors in such a manner that the ability of the short wall machines to form sump and kerf cuts may be utilized for placing the simple conveyors in such positions for causing the latter to be automatically loaded by the falling of loose coal thereupon.

Other objects and advantages of the invention will be apparent during the course of the following description.

In the accompanying drawings forming a part of this specification and in which like numerals are employed to designate like parts throughout the same,

Figure 1 illustrates a horizontal sectional view taken through a room in a coal mine and shows a pile of loose coal which has been shot down from the face of the room with the loader embodying this invention in a position ready to be dumped under the said loose pile of coal,

Figure 2 is a similar view to Fig. 1 with the exception that the coal loader is illustrated after it has been dumped under the pile of loose coal and is being moved laterally along the floor of the room for the purpose of causing the coal to fall upon the conveyor portion of the loader whereupon the conveyor may carry the coal to the mine car illustrated as being partially filled with coal.

Figure 3 is a side elevational view of the loader embodying this invention mounted upon the transportation truck employed for carrying the loader from one point of operation to another,

Figure 4 is a top plan view of Fig. 3.

Figure 5 is a transverse sectional view taken through the forward portion of the loader illustrated in Figs. 1 to 4,

Figure 6 is a transverse sectional view taken through the rear portion of the loader illustrated in Figs. 1 to 4 inclusive,

Figure 7 is a detail top plan view of the front end portion or wedge-shaped shoe of the conveyor portion of the loader,

Figure 8 is a side elevational view of Fig. 7,

Figure 9 is a transverse sectional view taken upon line IX-IX of Fig. 8,

Figure 10 is a detail plan view of the upper transfer board illustrated in section in Fig. 5 and in top plan in Figs. 1 and 4,

Figure 11 is a top plan view of a connector pan illustrated in section in Fig. 6, and

Figure 12 is a rear end elevational view of the pan illustrated in Fig. 11.

In the drawings, wherein for the purpose of illustration is shown a preferred embodiment of this invention, and wherein only the features of construction of the shortwall mining machines and the simple conveyors that are of importance to this invention are shown, the numeral 5 designates the body portion of a conventional form of shortwall mining machine which further includes the cutter bar 6 that extends longitudinally outwardly from one end of the body portion 5 and further extends longitudinally through the under portion of the body 5 of the machine. Carried by the outer end of the cutter bar 6 is a sprocket wheel 7 which supports and guides the chain type of cutter 8, as illustrated. Positioned in proximity to the inner end of the cutter bar 6 is the main drive sprocket 9 which is employed for driving the chain cutter.

It is to be understood that suitable mechanism is positioned within the body portion 5 of the shortwall mining machine for rotating this main drive sprocket 9 at a desired speed for properly operating the chain cutter 8.

When this shortwall type of mining machine is used as a complete unit for undercutting or forming a kerf along the face of a room or entry, the said machine is placed upon the floor of the room and is driven longitudinally forwardly by means of a feed rope or chain for forming a sump cut into the face of the room adjacent one wall or rib of the latter. In Figs. 1, and 2 the mechanism employed for moving this shortwall machine is clearly illustrated. The shortwall mining machine is provided with

100

105

110

a driving sheave 10 which is mounted upon a vertically extending shaft and is driven by the mechanism housed within the body portion of the apparatus. The machine is further provided with a rear sheave 11 and the opposite side sheaves 12 and 13. The shortwall machine is further provided with a front sheave 14 which is carried laterally of one side face of the same. A feed rope or chain 15 is passed around these various sheaves 10 to 14 inclusive in the manner illustrated in these three figures and is connected at its opposite ends to anchor-jacks 16 which are properly positioned in a well known manner for permitting the desired movement of the shortwall mining machine to be accomplished. After the shortwall mining machine has been driven longitudinally forwardly for permitting the cutter bar 17 with its chain cutter to form the sump cut, the anchor-jacks 16 are then shifted for permitting the operation of the feed rope or chain 14 for causing the shortwall mining machine to be moved laterally over the floor 25 of the room or entry. This lateral movement of the machine with the cutter chain traveling in the proper direction will cause a kerf cut to be formed along the base of the face of the room.

30 The type of simple conveyor employed in connection with this invention includes a frame which consists of the channel iron side plates 17 which are constructed to form the horizontally extending forward end portion —a—, the rearwardly inclined portion —b— and the rear edge portion —c—, the latter portion being vertically pivotally connected to the upper end of the inclined portion —b— for permitting the free end 40 of the portion —c— to be regulated to accommodate mine cars of different heights. These sections —b— and —c— are connected at their adjacent ends by the barrel joint 18. In Figs. 5 and 6 some of the detail features of construction of this simple conveyor type of apparatus are illustrated as consisting of a bottom plate 19 which connects the side plates 17 of the conveyor frame and the trough plate 20 which is connected to the inner faces of the side plates 17 by the angle irons 21 which extend longitudinally of said side plates. Suitably secured to the upper edge portion of the side plates 17 are the longitudinally extending angle iron guards 22 which are also employed for guiding the coal in its travel along the conveyor. In Fig. 8 the channel side plates 17 are illustrated as being beveled at their forward ends, as at 23 and are shown as terminating inwardly of the forward transverse edge 19^a of the bottom plate 19. Secured to the upper beveled edges 23 of these side plates is an inclined top plate 24 which is formed with a horizontally extending portion 24^a at its rear

edge and a horizontally extending portion 24^b at its forward edge, the rear portion 24^a being adapted for connection with the upper edges of the side plates 17 while the front horizontal portion 24^b is riveted to the projecting portion 19^a of the bottom plate 19. It will be seen that the end portions 19^a and 24^b are forged to a chisel edge for the purpose to be described at a later point. It will, also, be seen that the structure illustrated in Figs. 8 and 9 form a wedge-shaped shoe at the forward end of the conveyor.

In Fig. 8, the forward end portion of the side plate 17 is illustrated as being provided with a bearing 25 which is employed for receiving the front shaft 26 which carries the rollers 27 that are adapted for supporting the conveyor chain. In Fig. 3 the side plates 17 of the rear section —c— of the conveyor frame are illustrated as being provided with bearings 28 within which is journaled the rear shaft 29 that carries the rollers 30 that are employed for carrying the conveyor chain. This conveyor chain comprises the side chains 31, best illustrated in Fig. 5, to which are connected the cross flights 32. It will be seen by inspecting Fig. 5 that these cross flights rest upon the trough plate 20 during their travel from the front end of the conveyor frame to the rear end and that the flights rest upon the bottom plate 19 during their return travel to the front end of the frame.

The mechanism employed for driving this conveyor chain is mounted within a suitable housing 33 carried in proximity to the intermediate portion of the conveyor frame and includes a motor 34 having a pinion 35 mounted upon one end of its armature shaft. This pinion is in constant mesh with a gear 36 that is mounted upon a shaft 37 which extends in parallelism with the armature shaft of the motor 34. This shaft 37 carries a sprocket wheel 38 that receives a sprocket chain 39 which extends forwardly to drive the sprocket gear 40 mounted upon the shaft 41. This shaft 41 carries a conveyor chain drive 42 around which the conveyor chains 31 travel. There are also provided idlers 43 which support the conveyor chain on opposite sides of the chain drive 42.

As has been stated heretofore, this invention embodies the idea of operatively connecting the two independent unitary structures into one machine which is capable of being employed as a loader capable of performing the work now accomplished by the combination loader and conveyor types of mining machines. For the purpose of connecting the projecting portion of the cutter bar 6 to the forward section —a— of the conveyor, the inner side plate 17 of the latter is provided with any desired number of L-

shaped brackets 44 which may be welded or otherwise secured to the said side plate in such a manner that the longer arm portion of the same will extend laterally outwardly from the conveyor frame. The outer free ends of these brackets 44 are intended to be secured to the upper face of the cutter bar 6, as by the bolts 45 illustrated in Fig. 5. The body portion 5 of the shortwall mining machine and the casing 33 of the conveyor are to be suitably connected by a flat pan 46 which extends entirely under the bottom portion of the parts of the shortwall mining machine and conveyor just referred to. This pan 46 is illustrated as having one longitudinal edge of the same turned upwardly to form a flange 47 that is intended to flushly engage the outer face of the side flange 48 of the trough-shaped housing 49 which is formed in the lower portion of the body 5 of the shortwall mining machine for encasing the portion of the cutter chain and the cutter bar that are positioned within this body portion of the machine. Secured to the upper face of this pan 46 in a position to extend transversely of the rear end of the trough 49 in proximity to the periphery of the main drive sprocket 9 is an upstanding shield 50 which is of arcuate formation for the purpose of partially conforming with the path of travel of the cutter chain as it is carried around the main drive sprocket 9. The purpose for this shield will be set forth at a later point.

In Figs. 1, 4 and 5 the forward section —a— of the conveyor and the projecting portion of the cutter bar 6 are illustrated as having associated therewith what may be termed an upper transfer board 51 which is shown in plan in Fig. 10. This upper transfer board is intended to be suitably bolted to the upper face of the projecting portion of the cutter bar 6, as by the bolts 52 for causing the transfer board to extend longitudinally of the cutter bar and to bridge the gap between the side of the cutter bar and the adjacent side plate 17 of the conveyor. For the purpose of maintaining this upper transfer board in an inclined position, as best illustrated in Fig. 5, a plurality of blocks 53 are mounted upon the upper face of the cutter bar 6 and have the transverse intermediate portion of the upper transfer board resting thereupon and secured thereto by suitable bolts or rivets 54. The free edge of this transfer board is illustrated in Figs. 1, 4 and 5 as projecting inwardly of the guide angle iron 22 carried by the adjacent side of the conveyor frame for the purpose of permitting articles pushed over the free edge of this transfer board to drop upon the conveyor chain carried by the conveyor section —a—.

In Fig. 5 there is illustrated what I prefer to term an under transfer board 55 which is of reversely curved formation in cross-section and is secured to the inner side plate 17 of the conveyor frame by any desired number of brackets 56, which extend from the lower edge of this under transfer board, to the outer face of the side plate 17, as illustrated. The upper portion of this under transfer board 55 may be suitably secured to the upper edge of the side plate 17 or the angle iron guide 22 in any desired manner for positioning the free longitudinal edge 55a over the conveyor chain, as best illustrated in Fig. 5. The purpose for this under transfer board will also be described at a later point.

In Figs. 3 and 4, there is illustrated a transportation truck consisting of the body portion 57 which is suitably carried by the track engaging wheels 58. This transportation truck is intended to be employed for carrying this loader from one point of operation to another and for permitting the said loader to be easily placed thereupon and removed therefrom.

The preferred method of mining coal when this improved form of loader is employed may be set forth as follows:—

It is to be understood that the shortwall mining machine is first employed as an independent unit and is moved into a proper room or entry for the purpose of forming a kerf along the lower portion of the face of the said room or entry. The operation of this shortwall mining machine while forming this kerf cut has been described heretofore and need not be repeated at this point. After the kerf cut has been formed, augers are then used for drilling holes into which the explosives are placed. After the explosives have been discharged for shooting down the coal which has been undercut by the kerf formed by the shortwall mining machine, the coal will assume the appearance as illustrated in Figs. 1 and 2, or in other words, the coal will be loosely piled upon the floor of the room or entry adjacent the uncut face of the same. This improved form of loading-out machine is then intended to be placed in operation.

After the shortwall mining machine has been used for forming the kerf desired, the same may be connected to or united with the simple form of conveyor also illustrated in the drawing by connecting the outer ends of the brackets 44 to the projecting portion of the cutter bar 6 and by connecting the pan 46 to the body portion of the shortwall mining machine and the housing 33 of the conveyor. The upper transfer board should then be suitably placed in position by connecting the same to the projecting portion of the cutter bar 6. The under transfer board 55 may preferably be left in its operative position upon the conveyor both

while it is connected to or disconnected from the shortwall mining machine. After these units have been connected, the same may be mounted upon the transportation truck 53 and carried to the first point of operation where they may be unloaded from the truck and placed on the floor of the room or entry, as illustrated in Fig. 1. The feed rope or chain 15 with the anchor-jacks 16 should then be arranged substantially as illustrated in Fig. 1, whereupon the loading-out machine will be in readiness for operation. The mine car 59 mounted upon the track 60 may then be placed under the free end of the conveyor section —c—, as illustrated in Figs. 1 and 2.

After the cutter chain 8 is placed in motion and the motor 34 started for driving the conveyor chain flights rearwardly along the trough plate 32 toward the mine car 59, the feed rope or chain 15 may then be operated by means of the driving sheave 10 for causing the projecting portion of the cutter bar 6 and the parallel front section —a— of the conveyor to be dumped under the pile of loose coal in close proximity to the side wall or rib of the room. Fig. 1 illustrates the improved form of loading-out machine embodying this invention in position for starting this sump cut. The wedge-shaped shoe formed on the forward end of the conveyor frame will permit the same to be forced under the pile of coal without producing any great amount of friction or resistance to the movement of the same. The travel of the cross flights 32 in a direction toward the mine car 59 will rapidly carry the loose coal positioned above the front section —a— of the conveyor back to the said mine car. After the apparatus has been dumped under the pile of loose coal, the anchor-jacks 16 may be shifted into substantially the positions illustrated in Fig. 2. The shortwall mining machine, by its standard equipment, may then be moved laterally over the floor of the mine room or entry and will drag the conveyor along with it. The cutter chain 8 of the shortwall mining machine will form a kerf or in other words will cut a path underneath the pile of loose coal for permitting the travel of the projecting portion of the cutter bar 6 and the front end section —a— of the conveyor laterally over the floor of the room. This lateral movement of the loader will cause the coal to fall upon the conveyor and be carried rearwardly to be dumped into mine cars located beneath the rear end of the conveyor section —c—. The upper transfer board 51 will bridge the space between the projecting portion of the cutter bar 6 and the section —a— of the conveyor and will cause the coal to be pushed thereover onto the conveyor. Fig. 2 shows the loader after

it has been dumped under the pile of coal and has been started on its lateral movement over the floor of the mine.

It will be clearly seen that when the loader is dumped under the pile of loose coal, some of the latter will collect between the adjacent faces of the cutter bar 6 and the conveyor frame. The inward travel of the cutter chain along this side of the cutter bar will have a tendency to carry this coal rearwardly along one side of the trough 49 which surrounds the cutter bar and cutter chain while it is traveling within the body portion 5 of the machine and will be guided around the main drive sprocket 9 by the arcuate shield 50 whereupon this coal will be carried forwardly by the cutter chain and will be returned to the pile in advance of the cutter bar. During the lateral movement of this loader over the floor of the mine, the slack coal will also be dealt with in the same manner and the under transfer board 55 will further aid in cleaning up this slack coal by substantially scooping up the same and causing it to be placed upon the conveyor.

It is very apparent that while the independent elements embodying this invention are illustrated as being united or connected in such a manner that they must be moved laterally toward the left for causing the same to properly operate, these independent units may be readily connected together for permitting the entire device to be moved laterally toward the right for causing the same to perform its intended work, the cutter chain being arranged to travel in the opposite direction when the two units are connected for traveling toward the right.

It is now believed that the construction and operation of this improved loader will be clearly understood from the above detail description. It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In a coal mining machine, a horizontally extending kerf cutter having a longitudinally projecting cutter bar adapted for being moved either longitudinally or laterally for forming a kerf cut under a pile of loose coal with said cutter bar, a conveyor secured to the body portion of said kerf cutter and having a portion projecting in spaced parallelism with said cutter bar whereby when the latter is forming said kerf the projecting portion of said conveyor will be moved through said kerf and will carry

away the coal falling thereupon, and means carried by said cutter bar for preventing coal from falling into the space between the cutter bar and the adjacent portion of said conveyor when the same are moved laterally under the pile of loose coal.

2. In a coal mining machine, a horizontally extending kerf cutter having a longitudinally projecting cutter bar adapted for being moved either longitudinally or laterally for forming a kerf cut under a pile of loose coal with said cutter bar, a conveyor secured to the body portion of said kerf cutter and having a portion projecting in spaced parallelism with said cutter bar whereby when the latter is forming said kerf, the projecting portion of said conveyor will be moved through said kerf and will carry away the coal falling thereupon, and means removably secured to the cutter bar and extending longitudinally thereof for preventing coal from falling into the space between the cutter bar and the adjacent portion of said conveyor when the same are moved laterally under the pile of loose coal.

3. In a coal mining machine, a horizontally extending kerf cutter comprising a body portion and a cutter bar projecting therefrom adapted for forming a kerf cut under a pile of loose coal with said cutter bar, an endless conveyor secured to the body portion of said kerf cutter and having a portion projecting in spaced parallelism with said cutter bar whereby when said cutter bar is forming said kerf the projecting portion of said conveyor will be moved through said kerf and will carry away the coal falling thereupon, and means carried by said cutter bar and overhanging the adjacent portion of said conveyor for preventing coal from falling into the space between the same when moved laterally under the pile of loose coal.

4. In a coal mining machine, a horizontally extending kerf cutter comprising a body portion and a cutter bar projecting therefrom adapted for forming a kerf cut under a pile of loose coal with said cutter bar, an endless conveyor secured to the body portion of said kerf cutter and having a portion projecting in spaced parallelism with said cutter bar whereby when the latter is forming said kerf the projecting portion of said conveyor will be moved through said kerf and will carry away the coal falling thereupon, and a transfer board carried by said cutter bar and overhanging the adjacent portion of said conveyor for preventing coal from falling into the space between the same.

5. In a coal mining machine, a horizontally extending kerf cutter comprising a body portion and a cutter bar projecting therefrom adapted for forming a kerf cut under a pile of loose coal with said cutter bar, an endless conveyor secured to the body por-

tion of said kerf cutter and having a portion projecting in spaced parallelism with said cutter bar whereby when the latter is forming said kerf the projecting portion of said conveyor will be moved through said kerf and will carry away the coal falling thereupon, and an imperforate transfer board extending longitudinally of said cutter bar and removably secured to the top face thereof for bridging the space between the cutter bar and the adjacent portion of said conveyor.

6. In a coal mining machine, a horizontally extending kerf cutter comprising a body portion and a cutter bar projecting therefrom adapted for forming a kerf cut under a pile of loose coal, an endless conveyor secured to the body portion of said kerf cutter and having a portion projecting in spaced parallelism with said cutter bar whereby when the latter is forming said kerf the projecting portion of said conveyor will be moved through said kerf and will carry away the coal falling thereupon, and a vertically inclined board carried by the inner side of the projecting portion of said conveyor and extending laterally with its free edge underlying the path of travel of the cutters on the cutter bar for scraping up coal between the cutter bar and the conveyor as the same are moved laterally through said kerf.

7. In a coal mining machine, a horizontally extending kerf cutter comprising a body portion and a cutter bar projecting therefrom adapted for forming a kerf cut under a pile of loose coal, an endless conveyor, a detachable pan for connecting the intermediate portion of said conveyor to the body portion of said kerf cutter, and means for detachably connecting the front end portion of said conveyor to the cutter bar whereby when the latter is forming said kerf the front end portion of the conveyor will be moved through said kerf and will carry away the coal falling thereupon.

8. In a coal mining machine, a horizontally extending kerf cutter comprising a body portion and a cutter bar projecting therefrom adapted for forming a kerf cut under a pile of loose coal, and endless conveyor, means for detachably connecting the intermediate portion of said conveyor to the body portion of said kerf cutter, a laterally projecting bracket carried by the front end portion of said conveyor for connecting the same to the cutter bar in spaced relation thereto whereby when the latter is forming said kerf the front end portion of the conveyor will be moved thru said kerf and will carry away the coal falling thereupon, and means detachably carried by the cutter bar for bridging the space between the same and the front end portion of the conveyor for preventing coal from falling therebetween.

9. In a coal mining machine, a horizontally extending kerf cutter comprising a body portion and a cutter bar projecting therefrom adapted for forming a kerf cut under a pile of loose coal, an endless conveyor, a pan detachably connected to the under faces of the body portion of the kerf cutter and the intermediate portion of the conveyor, and a laterally projecting bracket secured to the inner side of the front end portion of the conveyor and connected to the cutter bar whereby when the latter is forming said kerf the front end portion of the conveyor will be moved through said kerf and will carry away the coal falling thereupon.
10. In a coal mining machine, a horizontally extending kerf cutter adapted for forming a kerf under a pile of loose coal, said kerf cutter comprising a body portion, a cutter bar extending longitudinally through and projecting from one end of the body portion, a chain cutter carried by said cutter bar; an endless conveyor connected to the kerf cutter and having a portion extending in spaced parallelism with the projecting portion of said cutter bar for receiving coal falling thereupon during the forming of the kerf in said pile, and means associated with the inner end of the cutter bar for causing any coal drawn into said body portion by the chain cutter to be guided so as to be returned to the pile by the cutter chain.
11. In a coal mining machine, a horizontally extending kerf cutter adapted for forming a kerf under a pile of loose coal, said kerf cutter comprising a body portion, a cutter bar extending longitudinally there thru and projecting from one end, and a chain cutter carried by said cutter bar; an endless conveyor connected to the kerf cutter and having a portion extending in spaced parallelism with the projecting portion of said cutter bar for receiving coal falling thereupon during the forming of the kerf in said pile, and an arcuate guide associated with the inner end of the cutter bar for causing any coal drawn into said body portion by the chain cutter to be guided so as to be returned to the pile by the cutter chain.
12. In a coal mining machine, a cutter bar, a conveyor fastened thereto and arranged in spaced parallelism therewith, means for moving said members longitudinally and laterally over the floor of a mine, and a transfer board mounted upon the cutter bar and extending laterally to terminate above the conveyor.
13. In a coal mining machine, a cutter bar, a conveyor fastened thereto and arranged in spaced parallelism therewith, means for moving said members longitudinally and laterally over the floor of a mine, a transfer board mounted upon the cutter bar and extending laterally to terminate above the conveyor, and a second transfer board fastened to the inner side of the conveyor beneath the first mentioned transfer board and extending from the floor line to a point above the conveyor for scraping up loose coal from the floor and dropping it into the conveyor when the members are moved laterally.
14. In a coal mining machine, a cutter bar, a conveyor fastened thereto and arranged in spaced parallelism therewith, means for moving said members longitudinally and laterally over the floor of a mine, a transfer board mounted upon the cutter bar and extending laterally to terminate above the conveyor, a second transfer board fastened to the inner side of the conveyor beneath the first mentioned transfer board and extending from the floor line to a point above the conveyor for scraping up loose coal from the floor and dropping it onto the conveyor when the members are moved laterally, and a forwardly declining shoe carried by the front end of the conveyor for scraping up loose coal from the floor of the mine in front of the conveyor when the members are moved longitudinally.

In testimony whereof I affix my signature.
CHARLES A. WARDEN.
